CLAIM

The ornamental design for a shoe, as shown and described.

DESCRIPTION

FIG. 1 is a front perspective view of a shoe showing our new design;

FIG. 2 is an opposite side front perspective view thereof;

FIG. 3 is a side view thereof;

FIG. 4 is an opposite side view thereof;

FIG. 5 is a front view thereof;

FIG. 6 is a rear view thereof;

FIG. 7 is a rear perspective view thereof; and,

FIG. 8 is an opposite side rear perspective view thereof.

The broken lines within the photographic area show elements that form no part of the claimed design.
